UNITED STATES PATENT OFFICE.

EDWARD O. TINSLEY, OF BROOKLYN, NEW YORK, ASSIGNEE TO ROBERT GAIR COMPANY, OF NEW YORK, N. Y., A CORPORATION OF NEW YORK.

JOINT STIFFENER FOR FOLDING CONTAINERS.

Application filed April 16, 1922. Serial No. 554,932.

To all whom it may concern:

Be it known that I, EDWARD O. TINSLEY, a citizen of the United States, residing in Brooklyn, in the county of Kings and State of New York, have invented certain new and useful Improvements in Joint Stiffeners for Folding Containers, of which the following is a specification.

My present improvement relates to a new form of joint stiffening means for preventing the collapse of folding, scored, joints in foldable paste board display containers where scoring is used for predetermining the folding points in permitting said container or its component parts to be folded flat.

While my invention is herein shown in connection with display containers, it is noted that the invention as claimed is not limited in its use to containers nor to display devices.

Another object of my invention is to make such stiffening means integral with the box thereby obviating the necessity of providing a separate means therefor, and at the same time to provide that such a device be very quickly set into and out of operative position.

In the drawing herewith, Fig. 1 is a perspective view of a container showing the improvement thereon.

Fig. 2 is a sectional view, slightly enlarged, taken on the line A-B, Fig. 1, looking in the direction of the arrow.

Fig. 3 is a rear view of said container showing the easel or support portion partly folded.

Fig. 4 is a sectional view taken on the line 4-4, Fig. 2, looking in the direction of the arrow.

Fig. 5 is a sectional view taken on the line 5-5, Fig. 4, looking in the direction of the arrow.

While in Fig. 1, I have shown my stiffening device located upon an easel or tilting portion 1, which is integrally attached to the bottom of a collapsing or foldable container generally denoted by 2, it is obvious that other such jointures as may be found to require such joint reinforcement may be readily provided with my device.

In the present instance, however, I have preferred to show a simple form of use which may be more readily described and understood. The container shown in Fig. 2 is of the so-called easel or tilting type of

display container, wherein the container is provided with a folding or collapsing easel portion 1, usually integral with a portion of the box structure, and more generally foldable against the box structure in order to make it as nearly rectangular as possible so as to economize in shipping space, as is well known in the customary practice.

However, in containers of the type herein disclosed the weight of the goods carried or shipped therein is such that the easel portion 1, when opened out, and the container placed in display position, for exposing the goods, may collapse under the weight of a full container thereby defeating the purpose for which the easel portion 1 was designed.

Usually the collapse of the easel in a container of this class is also due to the fact that the scoring, indicated by the dotted lines 3 throughout the drawings herein, may be rather deeply done, and thus weaken the easel or supporting sections. In other instances, constant folding and opening of the easel portion 1 may further weaken the scoring so that its inherent stiffness is destroyed and the easel portion will then tend to remain in its folding position rather than in the extended and supporting position as shown in Fig. 1.

I have found in practice that while the easel portion 1 may be folded in a number of places, that there is generally one or more positions out of the plurality of scoring points that may be provided with a stiffening means without the necessity of having every scored point so provided. In the present instance, I have found that the folding points 4, Fig. 3, formed at one of the scoring points 3 when properly provided with stiffening means, will permit the easel to be set up to support any reasonable condition of load, and incidentally permit of a very large number of consequent collapsing and extending actions without undesirable collapse occurring when the box is set up for display.

My improved stiffening means consists in the provision, transversely to the line of scoring, of a bendable hinged, tab or lug 6, preferably of semi-circular form, which is blanked out of the wall of the side upon which the scoring occurs. In the present instance the tab member is preferably made with its largest diameter hingedly connected 110

to its associated side at a point 7, Fig. 5, so that in effect, when this tab is bent at a right angle to its inoperative position, it acts to bridge the scored line and thereby stiffens the scored member.

Naturally, in the process of manufacture, the cutting of the stiffener into the side wall and transversely to the scored line 3, as above noted, also permits the stiffener element to become itself scored so as to permit ready folding at the scored joint when the stiffener is in non-operative position, as is disclosed at 4, Fig. 3, wherein the easel portion is shown partly collapsed against the bottom of the box 2.

When the easel portion as shown in Fig. 3, is fully extended as in Fig. 1, the stiffener member lies in the plane of the wall and partakes of the extending action of its associated wall section, and after the easel portion 1 is extended into support position, then the stiffener element 6 is pushed inwardly by the finger thereby causing it to take the position as shown in Fig. 5, and, owing to the substantially right angle, shelf-like projection of the tab 6, across the line of scoring 3, the said scoring is prevented from being bent inwardly or outwardly, due to the transverse truss action caused by the re-arrangement of the tab 6 at right angles to the sides of the said easel portion 1 and transverse to the line of scoring 3.

It is obvious that various geometric forms of tabs may be cut in the box without departing from the spirit of the disclosure made herein, and it is also obvious that, while I have shown the stiffener tab as being integral with the side of the box and blanked therefrom, that other modifications may thus be made for the same purpose, all of which I would consider as being equivalent of the structure herein disclosed.

What I claim is:

45 1. In a device of the character described, a member provided with a line of fold, and a partially cut-out stiffening means disposed transverse to said line, said stiffening means being bendable upon a score line transverse to said line of fold.

50 2. In combination, a supporting device; and a supporting member provided with a

scored line of fold, providing relatively foldable sections; said member being provided with a stiffening means partially cut-out of both said foldable sections, said means being scored at its base portion and being disposable substantially perpendicular to said line to stiffen said member.

55 3. A foldable display container having a 60 scored foldable easel thereon, and a partially cut-out bendable stiffening means located transversely to the line of scoring, the said bendable means having its bending base developed transversely to the line of 65 said scoring.

4. A foldable display container of the class described, having a scored foldable portion and a bendable cut-out tab located transversely to the line of the scoring upon 70 said foldable portion, said tab being adapted to be bent at right angles to the plane of said foldable portion whereby to bridge and prevent inversion of the score on said portion.

5. In combination, a supported device, and a supporting member provided with a scored line of fold providing relatively foldable sections, and a single tab member being cut out of said foldable sections on both 75 sides of the fold line thereof, the said tab being provided with a score line at its base and transverse to the said fold lines, and being bendable at right angles to the said fold line whereby to hold said foldable sections against inversion.

6. A folding support for boxes of the class described comprising a section of said box being bendable to cause said support to lie flat to the box when in closed position 80 and provided with a partially cut-out tab portion for a single score at its base portion, the said score being formed at right angles to the line of scoring between sections of 85 said folding portion whereby when said tab is bent upon said score line, it forms an un-scored bridge portion located in such position as to prevent inversion of said foldable portion when the tab is bent at right angles to the plane of said folding portion.

EDWARD O. TINSLEY.
